May 20, 2021 (JP) 2021-010533

The ornamental design for a sterilization and deodorization device, as shown and described.

(51) **LOC (14) Cl.** **23-04**

DESCRIPTION

(52) **U.S. Cl.**

1. Sterilization and deodorization device

1.1 : Front

1.2 : Back

1.3 : Top

1.4 : Bottom

1.5 : Left

1.6 : Right

1.7 : Perspective

1.8 : Perspective
